WIRE WINDING DEVICE

Charles V. Lindbloom, Daytona Beach, Fla.

Application January 28, 1949, Serial No. 73,410

2 Claims. (Cl. 140—118)

1

This invention relates to winding devices, such, for example, as may be used for winding a wire, or the like, about another wire or a portion of the same wire.

A device of this nature is particularly useful in forming eyes in leaders for fish hook, but it is to be understood that this invention is not limited to such use. When made in appropriate sizes, a device made in accordance with this invention likewise is useful in the winding of wire, or the like, for other purposes, such for example, as wires used in connection with telephones, pictures, signs, fences, etc.

This invention has as its primary object to provide an improved winding device which is simple in construction, inexpensive to manufacture, easy to operate and which, when constructed for light work, such as leaders for fish hooks, may readily be carried in one's pocket, for use whenever required.

For convenience, this invention is shown in the accompanying drawings and described in this specification as embodied in a device adapted to form an eye in a leader for a fish hook but, as above stated, the invention is not limited to this particular embodiment or use.

In the drawings,

Fig. 1 is a front elevation of an eye-forming and wire winding device embodying the present invention.

Fig. 2 is a plan view thereof.

Fig. 3 is a rear elevation of the device shown in Figs. 1 and 2.

Fig. 4 is an enlarged detail horizontal sectional view taken through the handle end of the main frame of the device, showing the manner in which the wire is inserted into the device, and through the eye of a fish hook, preparatory to the winding operation.

Fig. 5 is an enlarged vertical section through the winding key as indicated by the line 5—5 in Fig. 1.

Fig. 6 is an enlarged horizontal sectional view taken substantially on the line 6—6 of Fig. 1.

Fig. 7 is a perspective view of a winding key, showing its relation to the wire at the beginning of a winding operation.

Fig. 8 is a perspective view of an arbor herein-after described, about which the eye in the leader is formed.

Fig. 9 is a view of a wire formed into an eye and wound by a device made in accordance with this invention.

Fig. 10 is a detail view of a leader having, at each end, an eye formed by the device shown in

2

Figs. 1, 2 and 3, one eye being shown attached to a conventional swivel and the other eye engaging the eye of a fish hook; the middle portion of the leader being broken away.

Referring more specifically to the drawings, the invention is disclosed as embodied in a winding device comprising a U-shaped frame F comprising upstanding legs 1 and 2 and a connecting base portion 3. Formed integral with the upper end of the leg 1 is a head 1^a and a handle 4 by means of which the device may be held while in use. The leg 2 is formed at its upper end with a head 2^a which is slotted at 5 to permit the insertion of a portion of the wire leader in which the eye is to be formed. A clamp screw 6, threaded through the upper portion of the head 2^a, is adapted to bear upon the wire to clamp it in the slot 5, for a purpose hereinafter to be described.

The head 1^a is formed with a vertical bore 7 which receives the shank portion 8^a of an inverted L-shaped arbor A formed at its upper end with an offset handle portion 8^b. The head 1^a is also provided with a horizontal slot 1^c and a clearance aperture 1^b which intersects the bore 7 and the slot 1^c, thereby providing, on the head 1^a, a pair of vertically spaced curved fingers f which embrace the shank 8^a of the arbor A. The shank of the arbor is formed with a vertical groove 8^c which is aligned with the clearance aperture 1^b in the head 1^a. Thus the eye of a fish hook h, a swivel s or other eyed element, may be placed against the side of the head 1^a with the eye-portion e thereof located in the groove 8^c in the arbor. With the parts in this position, one end of a wire leader w may be passed through the slot 1^c between the fingers f and through the eye e of the fish hook, as shown in dotted lines in Fig. 4.

Cooperating with the frame F and the arbor A is a winding key member K comprising a substantially cylindrical shank portion 9^a, a ring-like lower end portion 9^b which affords a finger-piece, and a reduced cylindrical upper end portion 9^c. The key member is formed with a central longitudinal bore 9^d and, in the portion 9^c with an upwardly inclined transverse slot 9^e which intersects the bore.

Operation

Assuming that the device is to be used to form a relatively small eye in a wire leader and to have that eye engage the eye of a fish hook, the operation of the device is as follows:

A fish hook h is placed against the side of the head 1^a of the frame F with the eye e thereof

in the groove 8^c in the arbor A, as shown in Figs. 2, 4 and 6. One short end portion w' of the wire w is then passed through the slot 1^c between the fingers f and through the eye e of the fish hook. The main portion of the wire is then turned clockwise (Figs. 2 and 4) about the arbor A and a portion thereof is passed laterally into the slot 5 in the head 2^a and beneath the clamp-screw 6 where it is clamped by tightening of the screw. The end portion w' of the wire is then inserted in the bore 9^d of the key K which is then turned and placed upon the wire w by hooking the slotted upper end of the key over the wire adjacent the frame head 1^a. This forms a loop p (Fig. 7) in the wire about the arbor A and places the main portion of the wire against the side of the end portion w' in the bore 9^d, as shown in Fig. 5. The key K and the portion of the wire in the bore 9^d are then turned about the clamped wire w, as indicated by the arrow X in Fig. 1. This wraps the end portion w' of the wire about the main portion thereof and tightens the loop p into a relatively small substantially circular eye E which encircles the arbor. As the coils c continue to be made by the turning of the key, that portion of the wire in the bore 9^d of the key is used up. This may be continued until the end of the wire emerges from the upper end of the bore in the key. This winding operation produces an eye E and a plurality of contiguous coils c as shown in Fig. 9. The hook-like portion H projecting from the last coil may then be cut off, as indicated at T in Fig. 9.

It is to be understood that swivels or other devices likewise may be attached to the wire w by the above described operation. Under certain conditions and for certain purposes, it may be desired to form eyes in wires without having any hook or other object connected thereto. This may be accomplished by following the operation described above and merely omitting the fish hook or other object.

After the eye E has been formed by the above described winding operation, the wire may be removed from the device by loosening the clamp screw 6 and withdrawing the arbor A from the bore 7 and the eye E.

Having thus set forth the nature of the invention, what I claim herein is:

1. In a device for forming an eye at the end of a wire and securing the same to the eye of a fish hook or the like in which the wire is passed through the eye of the fish hook and a free end portion of the wire is wrapped about the wire; the improvement which comprises a U-shaped frame affording two spaced heads, means to hold a wire in one of said heads, the other of said

heads having a slot, a bore intersecting the slot and a clearance space intersecting the slot and extending to said bore, an arbor about which the wire is to be looped during the formation of the eye thereof removably mounted in said bore and extending across said slot, said arbor having a groove alignable with said clearance space to receive a part of the eye of the fish hook placed in the clearance space and to align the eye with said slot, whereby a wire looped about the arbor during the formation of the eye of the wire will pass through the eye of the fish hook.

2. In a winding device for forming an eye at the end of a wire in which the wire is formed into a loop and an end portion of the wire is wrapped about the wire; the improvement which comprises a U-shaped frame affording two spaced heads, a first of said heads having a slot with opposite sides thereof terminating, respectively, at the side of said first head closest the second head and at the opposite side of said first head, means for holding a wire in said slot, the second of said heads having a slot opening at the side thereof closest the first head, an arbor about which a wire to be clamped in said first head may be looped to form the eye mounted in said second head and extending transversely of and across the slot in the second head, and a clearance space formed in said second head and extending to said arbor, whereby a member may be inserted in said clearance space and have the wire looped around it as well as the arbor before the end portion of the wire is wrapped about the wire to form the eye.
